CONTROL SYSTEM

Filed Sept. 21, 1939

UNITED STATES PATENT OFFICE

2,248,350

CONTROL SYSTEM

Robert H. Hill, Anderson, Ind., assignor to General Motors Corporation, Detroit, Mich., a corporation of Delaware

Application September 21, 1939, Serial No. 295,857

6 Claims. (Cl. 250—20)

The present invention relates to improved electrical means for moving a control element to predetermined positions. More particularly it relates to automatic tuning mechanism for radio receivers in which the tuning shaft is moved to any one of a plurality of predetermined positions corresponding to broadcasting station frequencies by station selector mechanism located at a distance from the automatic positioning mechanism.

In automatic tuning mechanisms of the type described it is necessary to provide means for reversing an electric motor to rotate a tuning shaft in either direction and to cause the shaft to be stopped accurately in one of a plurality of positions in order to obtain sharp tuning. It is also necessary to provide a plurality of readily adjustable means for changing the positions at which the shaft is to be stopped in order to obtain a different selection of broadcasting frequencies to suit the locality in which the receiver is operated. This adjustable feature is especially desirable for receivers installed in vehicles traveling between different localities. In prior mechanisms of this type remote controlled mechanisms have been used in which electrically actuated mechanical detents were used for stopping rotation of the shaft. These mechanisms included electrical contact means movable by the detents to break electrical circuits for the shaft driving means and were satisfactory for stopping the shaft in definite positions but in case of binding of the detents the electrical circuits were not interrupted and failures of the electrical driving mechanism occurred.

The primary object of the present invention is to provide a simplified remotely controlled automatic tuning mechanism in which angularly movable and manually adjustable electric contact mechanisms only are used to control the electrical driving means so that the tuning shaft may be rotated in either direction to a plurality of predetermined positions.

Another object is to provide electrical means for mechanically disengaging the electrical driving means from the tuning shaft to stop it in a precise angular position with no overrunning.

A further object is to provide separate energization means for the control circuits and the circuit to the electrical driving means to insure long contact life.

Other objects of the invention and means by which the above objects are accomplished, as well as the advantages derived by the use of these improvements over prior devices of this

type, will be referred to in the course of the following description.

For a more complete understanding of the invention reference will be made to the single accompanying drawing showing the structure in diagrammatic form and the circuits for controlling and actuating the tuning shaft.

Referring to the drawing by reference characters, 1 designates a radio receiving set having 10 a radio speaker (not shown) and a tuning shaft 3 provided with a conventional control knob 5 fixed thereto for manual rotation. A reversible electric motor 7 is operably connected to rotate the tuning shaft by means of the gears 9 and 11 fixed respectively to a motor shaft 13 and to a hollow shaft 15 rotatably mounted on the tuning shaft 3 and having a clutch disc 17 fixed thereto. A complementary clutch disc 19 axially movable on and rotatable with the tuning shaft 3 is normally held out of engagement with the clutch disc 17 but is movable into engagement with it by an electromagnetic winding 21 fixed thereto and having end connections 21 and 23. The connection 21 is connected to the 25 motor armature winding by a conductor 25 and the other connection 23 is grounded.

The motor 7 has a conventional armature winding, one side 27 of which is connected to ground and the other side is permanently connected internally to the conductor 25 and to two exciting field windings having separate external end connections 29 and 31 extending to fixed contacts 33 and 35 of a relay indicated generally at 37. Excitation of either of the field 35 windings causes opposite rotation of the motor shaft 13.

The relay 37 comprises two armatures 39 and 41 pivotally mounted at points 43 and 45 intermediate their ends on a stationary insulated 40 support 47 and are connected together for simultaneous parallel rocking movement about these points by an insulated connecting rod 49 pivoted to each. A blade spring 51 having one end fixed to the support 47 and the other fixed 45 to the connecting rod 49 serves to hold both armatures in their open circuit position with the armature 41 out of contact with the fixed contacts 33 and 35 and the armature 39 out of contact with fixed contacts 65 and 67 to be referred to subsequently. The armature 41 is connected by a conductor 53 to one side of a source of current or battery 55, the other side 57 of which is grounded. Both of the armatures 39 and 41 are provided with contacts 59 fixed on opposite ends thereof. The armature 41

serves to energize the motor armature through either field connection 29 or 31 when either of the contacts 59 of the armature 41 is moved into contact with either of the fixed contacts 33 or 35 located adjacent thereto. The armature 39 is connected to ground by a conductor 61 and serves to ground a conductor 63 included in the speaker circuit associated with receiver to mute the speaker when either of the contacts 59 of the armature 39 makes contact with either of the fixed contacts 65 or 67, both of which are connected to the ground conductor 61. Simultaneous parallel rocking movement of the armatures 39 and 41 in either direction about their pivots 43 and 45 respectively is accomplished by two relay electromagnets 69 and 71 located adjacent the ends of the upper armature 39 which attract the respective ends thereof when energized individually and move both armatures in either direction. The relay electromagnets 69 and 71 are separately connected to individual bus bars 73 and 74 by conductors 75 and 77 and have a common connection 79 extending between the opposite end of their individual windings which is connected to a bus bar 81 by a conductor 83.

Either of the relay electromagnets is excited from any one of a number of parallel branch circuits, three of which are shown, connected to a bus bar 85 which is connected to the battery 55. Any number of such circuits may be used. Each of these circuits is connected by conductors 87a, 87b and 87c to the bus bar 85 and include identical manually operable selector switches indicated generally at 89a, 89b and 89c which may be located at a distance from the receiver and motor and are provided with electromagnetic holding coils 97a, 97b and 97c. Identical shaft positioning switches generally indicated at 103a, 103b and 103c are also included in each of these circuits. The selector switches and shaft positioning switches comprise identical parts which operate in like manner and the following description will therefore be confined to one of these circuits only which includes a single switch of each type.

The selector switch 89a consists of an armature 91a manually movable to bridge contacts 93a and 95a. An electromagnetic holding coil 97a located adjacent the armature 91a serves to attract and hold it in bridging relation with the contacts 93a and 95a when energized but it is incapable of attracting and moving the armature from its normal open position in which it is shown. One end 99a of the holding coil 97a is connected to ground and its opposite end 101a is connected to the bus bar 81 to which the electromagnetic relay coils 69 and 71 are connected so that either of these electromagnetic relay coils and the holding coil 97a may be connected in series to ground through the end 99a of the holding coil 97a. Switch contact 93a is connected to the conductor 87a and contact 95a is connected to a shaft positioning switch 103a by a conductor 105a.

The shaft positioning switch 103a comprises an insulating disc 107a having spaced arcuate contacts 109a and 111a imbedded in the disc and having their external surfaces flush with the peripheral surface of the insulated segment 113a of the disc separating the ends of these contacts. The disc 107a is fixed to the tuning shaft 3 for rotation thereby and has three brushes 115a, 117a and 119a suitably held in contact with its peripheral surface. The brush

115a is connected to the conductor 105a and is supported on a brush holder 121a provided with an arcuate slot 123a through which a stud 125a projects. The stud 125a is attached to a fixed support 127a and the brush and the brush holder may be angularly adjusted to any one of a plurality of angular positions with respect to the disc 107a and the fixed support 127a and may be locked thereto by means of a nut 129a threaded on the end of the stud 125a. In the position shown brush 115a is in contact with the segment 113a only. The brushes 117a and 119a are spaced angularly to either side of the adjustable brush 115a and are suitably held in a fixed angular position so that each remains in electrical contact with the individual arcuate contacts 109a and 111a for all angular positions of the disc and tuning shaft. The brush 117a in contact with the arcuate contact 109a is connected to the bus 73 by a conductor 131a and the brush 119a in contact with arcuate contact 111a is connected to the bus bar 74 by a conductor 133a. As the relay electromagnets 69 and 71 are connected separately to the bus bars 73 and 74 by conductors 69 and 71, either of the electromagnets 69 or 71 may be energized through any of the shaft positioning switches 103a, 103b and 103c, depending upon the angular relation of the insulating disc segments 113a, 113b and 113c and arcuate contacts adjacent thereto are in relation to the adjustable brushes 103a, 103b and 103c when any one of the circuits in which these shaft positioning switches are connected is selectively connected to the battery upon closure of any one of the selector switches 89a, 89b or 89c.

The operation of the automatic tuning mechanism is as follows:

With the parts in the position shown when the selector switch 89b is closed a control circuit is completed through the following conductors: battery 55, conductors 85 and 87b, contact 93b, selector switch armature 91b, contact 95b, conductor 105b, brush 115b, arcuate contact 109b, brush 117b, conductor 131b, bus 73, conductor 75, relay electromagnet winding 69, conductors 79, 83, bus 81, conductor 101b, electromagnet holding coil winding 97b and to ground through conductor 99b. Energization of the holding coil attracts and holds the selector switch armature 91b in the closed position to maintain this circuit energized. Energization of the relay electromagnet 69 attracts and moves the left end of both relay armatures upward to establish the following connections. The relay armature 39 grounds conductor 63 of the speaker circuit to mute the speaker, not shown, and the relay armature 41 connects the motor 7 to the battery 55 by the following conductors: conductor 53, armature 41, contacts 59 and 35, field conductor 31 and through the armature winding to ground by the conductor 27. The parallel circuit connection 25 from the motor armature winding to the electromagnetic clutch winding is also energized to cause engagement of the tuning shaft disc 19 with the motor-driven disc 17.

Energization of the field conductor 31 causes the motor to rotate the tuning shaft counter-clockwise as indicated by the arrow on the disc 107b, thereby causing the insulating segment 113b to move toward the brush 115b and assume the same angular position with respect to the center line of the shaft that the brush occupies which causes the control circuit to be opened and the motor and clutch circuits con-

trolled thereby to open. The tuning shaft is thus rotated to a definite angular position and stopped by disengagement of the clutch mechanism. The tuning shaft which is mounted in the conventional manner and has the usual friction means associated therewith to prevent movement, stops instantaneously in this position and the motor armature and shaft having some inertia may continue to revolve, but as the clutch is disengaged the shaft will not continue to overrun with the motor.

With the parts in the position shown, it is evident if the shaft positioning switch 103c is energized by its respective selector switch 93c, the motor will rotate the shaft clockwise from the position shown to a definite angular position corresponding to the angular position which the respective adjustable brush 115c occupies. In this case, however, the other relay electromagnet 71 will be energized by the conductors 77, bus 74, conductor 133c, brush 119c, arcuate contact 111c which is now connected to the battery by the selector switch 103c and the parallel conductors as before enumerated but having a "c" subscript. The relay armatures 39 and 41 will now be moved in the opposite direction so that the field connections 29 will be energized and the tuning shaft will rotate clockwise as indicated by the arrow on the disc 107c until the insulating segment 113c breaks all circuits by moving under the adjustable brush 115c thus stopping the tuning shaft in a different angular position.

It is evident from the above description that the stopping position of the tuning shaft is determined by the position of the adjustable brush and that the motor circuit connections controlled by any parallel control circuit are such that the shaft is rotated in either direction to a definite angular position which can be varied by moving this brush angularly with respect to any disc. The insulating segment is always rotated toward the movable brush from any angular position either side of the brush and it and the shaft is stopped at this position.

With this particular control consisting of only electrical contacts movable with respect to fixed and adjustably fixed contacts, any control circuit can be selectively energized by manually operable selector means which controls a separate motor circuit to cause rotation of the shaft in either direction to one of a plurality of predetermined positions where the shaft will be automatically stopped. Each position can be set by tuning the receiver to a certain broadcasting frequency by means of the tuning knobs and then moving the adjustable brush so that it is in mechanical contact with the insulating segment and out of electrical contact with the arcuate contacts adjacent thereto and then locking it in this position which is the position that brush 115a and segment 113a are shown in. As the control circuits are energized from the battery by a different circuit from the motor circuit all the contacts may be designed for low current flow to insure long life and trouble-free operation.

I claim:

1. In an automatic tuning mechanism for radio receivers comprising, a tuning shaft, an electric motor operably connected to drive the shaft, a source of current, a power circuit including said motor, said source of current and motor control means movable to establish forward and reverse driving connections to the motor but normally held in the open circuit position, and a control

circuit separately connected to said source of current including electromagnetic means for moving said motor control means, manually operable control circuit closing means having electromagnetic holding means therefor and switch means driven by said tuning shaft having an open circuit position for a given angular position of the tuning shaft and closed circuit positions on either side of this position to connect one or the other of said electromagnetic means and said electromagnetic holding means with said source of current.

5 2. In an automatic tuning mechanism for radio receivers comprising, a tuning shaft, an electric motor operably connected to drive the shaft, a source of current, a radio speaker circuit, a separate power circuit including the motor and the source of current, separate relay contacts in both of said above mentioned circuits normally biased 15 to their open circuit position and movable simultaneously to ground the speaker circuit and to establish forward or reverse driving connections to the motor, a pair of electromagnets for moving said relay contacts and a control circuit separately 20 connected to said source of current including said electromagnets, manually operable control circuit closing means and means operably connected to the tuning shaft for rotation thereby to open said control circuit in a definite angular 25 position of the control shaft and to close said circuit to energize one electromagnet or the other when moved to an angular position either side of this position to cause rotation of the shaft by the motor toward said definite angular position.

3. In an automatic tuning mechanism for radio receivers comprising, a manually rotatable tuning shaft, an electric motor for driving the shaft, means between the tuning shaft and motor engageable to cause rotation of the shaft by the motor, electromagnetic means for causing engagement of said means, a source of current, a circuit from said source of current to the motor, a circuit from the motor to the electromagnetic means, means in said motor circuit movable in either 40 direction from its normal open circuit position to establish forward or reverse rotation of the motor and tuning shaft and to control energization of said electromagnetic means, separate electromagnets for moving said last mentioned means either way from its normal position, a plurality of control circuits connected to said source of current, each of said control circuits including said electromagnets, a manually operable selector switch for closing one of said control circuits, 45 an electromagnetic holding coil for maintaining each switch in the closed position, and a contactor mechanism driven by said shaft to connect either of said electromagnets and said electromagnetic holding coils in the circuit for all angular positions of said tuning shaft either side of a definite angular position to cause rotation of the tuning shaft in either direction to the definite angular position at which said contactor mechanism opens said circuit to stop rotation of said tuning shaft.

4. In an automatic tuning mechanism for radio receivers comprising, a manually rotatable tuning shaft, a reversible electric driving motor, a clutch connected between the tuning shaft and the motor engageable to cause rotation of the shaft by the motor, a clutch engaging circuit connected to the motor and including an electromagnetic winding for engaging said clutch when the motor 70 is energized, a source of electrical energy, a motor

energizing circuit, means in said motor energizing circuit movable to establish forward and reverse driving connections of the motor and to normally open either or both of these connections, a control circuit including forward and reverse electromagnetic attracting means for moving said movable means included in the motor energizing circuit, a plurality of pairs of spaced contacts fixed to the tuning shaft for rotation therewith, conductors connected between each contact and each forward and reverse electromagnetic means and a plurality of energizing circuits for each pair of contacts, each including a brush angularly adjustable into contact with either contact of a pair, and a selector switch connected in series between each brush and said source of energy and manually movable to complete one of said energizing circuits and said control circuit switch and each brush to cause said tuning shaft to be revolved to one of a plurality of predetermined angular positions, each of which may be varied by the adjustably movable brush.

5. In an automatic tuning mechanism for radio receivers comprising, a tuning shaft, an electric motor connected to drive the shaft, a source of current, a circuit to the motor from the source of current, a relay armature in said circuit normally biased to the open circuit position and movable to establish forward and reverse driving connections to the motor, separate electromagnetic means to move said relay armature, a separate control circuit including the electromagnetic means, a plurality of control switches for said circuit, each of said switches comprising a rotatable insulating element attached to and driven by the tuning shaft, spaced arcuate contact on said element, conductors between each contact and each electromagnetic means, a brush angularly adjustable with respect to said contacts to make contact with either contact of said rotatable element or with a space therebetween, a plurality of parallel energizing circuits from said source of current to each of said brushes and a manually operable switch normally biased to

10 a neutral or open position included in each of the parallel energizing circuits and movable to its closed position for selectively energizing one of said control switches to cause rotation of the motor and tuning shaft to a definite angular position set by the angularly adjustable brush in the circuit so energized, each of said manually operable switches having electromagnetic holding means connected in series with said electromagnetic means for holding said switches in their closed position until said shaft is indexed to a definite position, whereupon said switches return to a neutral or off position.

15 6. In an automatic tuning mechanism for radio receivers comprising, a manually rotatable tuning shaft, an electric motor for driving said shaft, a clutch between said shaft and said motor engageable to cause rotation of the tuning shaft, electromagnetic means for engaging said clutch, a circuit from said motor to the electromagnetic means to energize said electromagnetic means with the motor, a source of current, a motor circuit connected to said source including means for controlling forward or reverse operation of the motor, said means including fixed contacts and an armature normally held out of contact with the fixed contacts but movable in opposite directions into contact therewith to establish forward or reverse driving connections of the motor and engagement of said clutch to cause rotation of the tuning shaft in either direction, a separate control circuit for said motor circuit connected to said source including a pair of electromagnets for attracting and moving said armature in opposite directions, and contact means operably connected to the tuning shaft for rotation thereby to complete said control circuit through one or the other of said electromagnets for all angular positions thereof except a definite angular position at which the control circuit is opened to stop rotation of the tuning shaft by opening of the motor circuit and disengagement of the clutch.

ROBERT H. HILL.

CERTIFICATE OF CORRECTION.

Patent No. 2,248,350.

July 8, 1941.

ROBERT H. HILL.

It is hereby certified that error appears in the printed specification of the above numbered patent requiring correction as follows: Page 4, first column, lines 19 to 22 inclusive, claim 4, strike out the words "switch and each brush to cause said tuning shaft to be revolved to one of a plurality of predetermined angular positions, each of which may be varied by the adjustably movable brush"; and that the said Letters Patent should be read with this correction therein that the same may conform to the record of the case in the Patent Office.

Signed and sealed this 19th day of August, A. D. 1941.

Henry Van Arsdale,
Acting Commissioner of Patents.
